ATTACHING MEANS AND ASSEMBLY
METHOD FOR SLOTTED TUBE AND TIP
MEMBER OF A MECHANICAL PENCILClifford N. Johnson, St. Louis, Mo., assignor to
Ritepoint Co., St. Louis, Mo., a corporation of
Missouri

Application August 7, 1948, Serial No. 43,147

5 Claims. (Cl. 120—18)

1

This invention relates to mechanical pencils, generally, and concerns itself more particularly with an improved means and method for securing the lead guide tubes thereof to their tip members.

It is an object of the invention to provide a simplified device and method for securing the lead guide tube of a mechanical pencil to its tip member which will prevent a separation of the parts, a turning of the tube in the tip member, and a loosening of the pencil's spiral feed.

It is also an object of the invention to provide a means and method for securing the lead guide tube of a mechanical pencil to its tip member, which will carry out the foregoing object, yet is simple and economical to make and practice.

Other objects and advantages will become apparent as the specification proceeds and a more comprehensive understanding of the invention will be afforded from the following detailed description when considered in conjunction with the accompanying drawings, in which

Fig. 1 is an exploded elevational view of a mechanical pencil unit embodying the instant invention;

Fig. 2 is a vertical sectional view of a tip member and lead guide tube employed in the unit illustrated in Fig. 1, taken along a line 2—2 indicated on Fig. 3 and showing a means for securing these parts together; and

Fig. 3 is a top view of the tip member and lead tube, only, of the unit illustrated in Fig. 1, showing these parts assembled.

Briefly stated, the invention contemplates a lead guide tube in which two transverse grooves are channeled on opposite sides of the tube near one of its ends. This particular end of the tube is inserted in a tube receiving bore of the tip member, to which it is to be attached, so that the top walls of the aforementioned grooves lie slightly above the mouth of the tube receiving bore. Within the tip member a larger bore, lying directly above the tube bore, is made which is adapted to receive a special swaging tool. This tool is hollow so as to slide over the lead guide tube and carries on its tool end a swaging die mounting three swaging elements. Two of the latter elements are arranged to upset material from the body of the tip member to form two small lugs, which, in the same swaging operation, are driven respectively into the grooves formed on the lead guide tube. These lugs engage the tube to hold it fast in the top member. The third swaging element forms a third lug and drives it into the slot of the lead guide tube, and drives it into the slot of the lead guide tube,

which prevents the same from turning in the tip member. With this method, the tube is secured to its tip member with a single swaging operation.

5 The above described means and method for securing a lead guide tube of a mechanical pencil to a tip member thereof finds its use and application in the device illustrated in Fig. 1. Here, a tip member 11 is provided in which there is drilled a plurality of connecting bores.

As shown in Fig. 2, a bore 12 is made at the top of the tip member 11, which may be termed as a swaging tool receiving bore. The bore 12, in turn, connects with a lead guide tube bore 13, and the latter communicates with a lead carrier bore 14. Finally, a lead bore 15 is made which connects with the bore 14.

The other elements of the mechanical pencil device, shown, are a bearing washer 16, a ferrule 17, spiral 18, lead carrier 19, lead guide tube 21, and bearing washer 22. As assembled, these parts are arranged as follows.

25 The lead guide tube 21 is attached to the tip member 11 in a manner later to be described, and the spiral 18 is staked into the ferrule 17 by means of a pin 23, carried on the former, engaging a groove 24 on the latter. The lead carrier 19 is passed into the lead guide tube 21 so that a lug 25 on the former rides in a longitudinally extending slot 26 in the latter. Next, the bearing washer 16, the spiral 18 and its attached ferrule 17 is passed over the lead guide tube 21 so that the former rests in the bottom of the bore 12 in the tip member 11 with the ferrule 17 bearing on the washer 16. The spiral 18 receives the lug 25 in a spiral slot 27 formed therein and is held in compression by the bearing washer 22, all in a manner well known to the art, a pin 28 holding the washer 22 on the tube 21.

35 The fact that the spiral 18 is held in compression between the bottom of the bore 12 and the bearing washer 22 attached to the tube 21, makes it necessary that the tube and tip member be securely attached to each other. Moreover, since it is a function of the lead guide tube 21 to guide the lead carrier 19 in a straight path, this tube must not turn in its bore 13.

40 Accordingly, the tube 21 is secured to the tip member 11 in the following manner. Two transverse grooves 29 and 31 (Fig. 2) are channeled in the lead guide tube 21 near the end thereof so their top walls lie slightly above the bottom of the bore 12 when the tube is in place in its bore 13. Next, by means of a special tool, two lugs,

or ears, 32 and 33 are swaged from the metal of the tip member 11 and driven, respectively, into the grooves 29 and 31. By means of the same special tool, and at the same time the lugs 32 and 33 are formed, a third lug 34 (Fig. 3) is struck from the metal of the tip member 11 and driven into the slot 26 of the tube 21, to prevent the turning of the tube in the tip member.

With regard to the economies of the means and method taught, it is to be pointed out that the grooves 29 and 31 are cut in the tube 21 at the same time, in the same operation and with the same die that cuts the tube to length. Further, the tube is secured in the tip member with a single swaging operation which is quickly and easily effected.

Various changes may be made in the details of construction, within the scope of the appended claims, without departing from the spirit of this invention. Parts of the invention may be used without the whole and improvements may be added while retaining some or all of the advantages of the invention.

What is claimed is:

1. A method for attaching a slotted lead guide tube to a tip member of a mechanical pencil, comprising the steps of boring said tip member to receive said tube, forming a transverse recess in the tube, inserting said tube within the bore, and swaging metal from the edge of said bore into said recess and the slot and in holding engagement with said tube at the point where said tube emerges from said bore.

2. A method of attaching a slotted lead guide tube to a tip member of a mechanical pencil comprising the steps of boring said tip member to receive said tube, counterboring said tip to form a swaging tube bore above and concentric with said tube bore, forming a transverse recess in said tube, and swaging lugs from the metal at the edge of said tube bore into recess and the slot and in holding engagement with said tube

at the point where said tube emerges from said bore.

3. In a mechanical pencil having a lead guide tube with a longitudinal slot and having its end inserted in a bore in a tip member, improved means for securing said tube in said tip member, comprising a lug formed from the body of said tip member at the edge of the bore turned into said longitudinal slot in said lead tube, a transverse channel in the tube, and a second lug similarly formed from the edge of said bore turned into said transverse channel in said tube.

4. In a mechanical pencil having a lead guide tube with a longitudinal slot and a tip member, improved means for securing said tube in a tube bore in said tip member, comprising a shoulder formed by a counterbore above and concentric with the tube bore in the tip member, a transverse channel in the tube, and at least two lugs struck from the edge of said shoulder and engaging respectively in said longitudinal slot and said channel in said guide tube.

5. In a mechanical pencil having a slotted lead guide tube and a tip member, means for securing said tube in a bore in said tip comprising a transverse channel in a wall of the tube at a point where the tube emerges from the tip in assembled relation, a first lug struck from the tip member at the mouth of the bore and turned into the groove, and a second lug similarly struck from the mouth of the bore and turned into a slot in said tube.

CLIFFORD N. JOHNSON.
